UNITED STATES PATENT OFFICE.

EARNEST C. HERRING, OF RENO, NEVADA.

GARMENT-SUPPORTING HOOK-PIN.

SPECIFICATION forming part of Letters Patent No. 750,032, dated January 19, 1904.

Application filed February 5, 1903. Serial No. 142,015. (No model.)

To all whom it may concern:

Be it known that I, EARNEST C. HERRING, residing at Reno, in the county of Washoe and State of Nevada, have invented a new and 5 Improved Garment-Supporting Hook-Pin, of which the following is a specification.

My invention is in the nature of an improved construction of combined pin and hook formed of a single wire member and especially adapted for supporting garments and to serve as a substitute for the ordinary button, and it comprehends a novel construction of hook and pin of a single wire member peculiarly bent up to produce a pendent hook member and upper transverse flat bearing portion for sustaining the said end in a flatwise relation to the article supported and the garment from which the said article is hung, a pin member for securing the device, and a 15 bracing portion for maintaining the several parts of the device in their proper correlative condition under ordinary strain when in use.

Subordinately my invention consists in a hook-pin of a single-wire strand having the 25 peculiar arrangement and detail combination of parts hereinafter fully described, and specifically pointed out in the appended claim, reference being had to the accompanying drawings, in which—

30 Figure 1 is a view illustrating my invention as in use. Fig. 2 is a perspective view of the preferred form of my improved hook-pin. Fig. 3 is a horizontal section of the same, showing its application to the garments and taken 35 practically on the line 3 3 of Fig. 1. Fig. 4 is a vertical section taken on the line 4 4 of Fig. 1. Fig. 5 is a detail cross-section on the line 7 7 of Fig. 2.

In the preferred form my improved hook-pin 40 consists of a single spring-wire member bent up to produce a flat body portion *a*, the lower end of which merges with an outwardly-projecting and upwardly-extending hook *b*. The side legs or members *a'* of the body *a* diverge 45 from the hook end, and each member *a'* at the upper end merges with a laterally-extended loop *c*, the outer end *c'* of which bends inwardly at right angles, as clearly shown in Figs. 2, 3, and 5, the reasons for which will presently appear, and one of the loops *c* combines with a sup-

plemental loop or catch *c*², that extends rearwardly at right angles and terminates in a downwardly-extending brace-piece *c*³, which connects with the adjacent side member *a'* at the neck of the loop portion *c* thereof. The leg 55 *a'*, opposite the leg combined with the brace and guide-loop *c*³, has its loop portion *c* terminate with a spring-coil *c*⁴, which in turn forms the inner or pivotal portion of the pin member *p*, which is of sufficient length to extend across 60 and coact with the loop members *c c*³ in the manner clearly understood from the drawings.

To firmly brace the two legs or members *a* and *a'* and hold them from spreading, a cross-piece 65 *d* joins the said members at a point just below the neck of the two members *c*.

By arranging the several parts of the hook-pin, as shown and described, I provide a strong, durable, effective, and conveniently-operated device.

70 The loops *c c*³ provide sufficient lateral bearing-surface to hold the device flatwise on and between the garments to which it may be attached, and, furthermore, where it is desired to permanently attach the device the said 75 loops form convenient attaching-thread-receiving eyes. Again, by forming the loop at one side with the supplemental guide portion *c*³ the latter acts as a pin catch and guide, and by bending the extreme ends of the loops 80 *c* inwardly at right angles the angle portions will serve two advantageous purposes—first, as end bearings for pressing inwardly against the inner garments or body of the user whereby to aid in sustaining the device in a proper 85 flat plane relatively to the garments to which it is secured and which it supports, and, secondly, to effectively hold back the inner garment adjacent to the pin-point and thereby not alone prevent the said point from penetrating the garment at the catch-loop portion of the device, but also prevent the pin from accidentally sticking the user. Another and important advantage in forming the several parts of the hook-pin, as stated, is that the 90 same can be readily bent up into shape and the parts interjoined to produce a rigid, strong, and economical device of this kind. In the manufacture of the same one end of the wire is formed with an eye *x*, and at a distance 100

from said eye equal the length of the cross-member d it is formed with a second eye or loop a' , and it is then bent up at right angles to produce the vertical brace or guide member c^3 , from whence it is bent to receive the pin-point-receiving and lateral loop c . The free end of the wire is then bent at right angles to form the neck c^x of the loop c , and it is passed through the eye a' , the portion 10 passing through the eye forming a leg or body member a' at one side, which member merges with the hook portion b , which is made by doubling the wire, as shown. From the hook b the free end of the wire is bent up 15 to produce the other leg or body member a' , which passes through the loop a , and at the point where it passes through the loop it is bent to produce the lateral loop c at that side and the spring-coil for the pin portion, which 20 is the terminal of the said wire member.

Having thus described my invention, what I claim, and desire to secure by Letters Patent, is—

A garment-holder, formed of a single piece 25 of wire bent to shape, and comprising oppo-

sitely-disposed side members, a bent hook merged with the lower end of said side members, each of said side members having a laterally and outwardly projecting bent loop disposed in the plane of the two side members, said loops having their outer ends bent rearward at right angles to the body of the device, one of the said side members having a spring-coil adjacent its lateral loop, and a transversely-projecting pin portion, the other 30 side member having a vertically-extended guide-loop disposed at right angles to its adjacent lateral loop, and including a vertical member extended over the inner end of the said adjacent loop, said extended portion being wound over the neck of the said extended loop, and extended transversely and connected with the opposite side member to form 35 a brace for the two side members, for the purposes set forth.

EARNEST C. HERRING.
